HYDRAULIC RELEASE FOR WELL BOTTOMS

Ruric N. Bean, Houston, Tex., assignor to Leslie
A. Layne, Houston, Tex.

Application September 27, 1937, Serial No. 165,798

13 Claims. (Cl. 166—20)

The invention relates to a well bottom assembly which can be lowered into position in the well bore and properly located by a tool which can be released from the well bottom by the application of hydraulic pressure.

In completing a well which has been drilled by the rotary method of drilling where the well bore is filled with drilling mud and it is usual to have a pressure present in the productive formation, it is desirable to lower the well bottom assembly, usually including a set shoe, strainer, liner and packer into the well as a unit and to wash the well and set the packer at a single operation or trip into the well with the setting string or flow tubing.

With the foregoing operation in mind, the present invention has been devised to provide a simple and economical apparatus whereby the washing operation may be performed and the setting string then released from the well bottom so that the packer may thereafter be set.

It is one of the objects of the invention to provide a setting tool connected at the base of the well bottom which can be released by hydraulic pressure.

Another object of the invention is to provide a plug movable by hydraulic pressure to effect release of the setting string from a well bottom.

Still another object of the invention is to provide a setting tool which is connected to the well bottom in such a manner that it may be released from the well bottom after the well has been washed.

Still another object of the invention is to provide a combination of devices whereby the washing and setting operation may be carried on in a well bottom without resorting to rotation of the setting string.

Other and further objects of the invention will be readily apparent when the following description is considered in connection with the accompanying drawings, wherein:

Fig. 1 is a side elevation of the upper end of the well bottom showing certain of the parts in section.

Fig. 2 is a side elevation of the well bottom as it continues below the part shown in Fig. 1.

Fig. 3 is a side elevation showing the lower end of the well bottom and is a continuation 50 below the lower end of Fig. 2.

Fig. 4 is a side elevation showing the construction just after the setting tool has been released.

Fig. 5 is a side elevation of another form of the base of the well bottom wherein hydraulic pressure is used to move the wash valve for the

purpose of closing the valve and also for the purpose of releasing the setting tool, the parts being in position just prior to release.

Fig. 6 is a side elevation similar to Fig. 5 and shows the wash valve closed and the setting tool released.

Figs. 7, 8 and 9 show transverse sectional views taken on the lines 7—7, 8—8 and 9—9 of Fig. 5.

When the well is to be completed, the drill bit and drill stem are withdrawn from the well and the casing such as 2 seen in Fig. 1 is then set in the well bore. The lower end of this casing usually terminates above the productive formation and it is then the practice to run the well bottom assembly into the well bore as a unit. The present invention contemplates the lowering of this well bottom assembly into the well bore by means of a setting string which will preferably be a string of tubing through which the production from the well will flow.

The setting operation is accomplished and the setting string then used as the flow tubing because it is permitted to remain in the well bore. In this manner considerable time and expense are saved in completing the well because it is not necessary to make a complete round trip of removing the setting string and inserting the tubing.

It will be understood that the setting string extends to the surface and will be connected to the threads 3 in the upper end of the coupling 4 shown at the top of Fig. 1. This coupling 4 has the wash pipe 5 connected to it and this wash pipe extends down through the well bottom shown in Fig. 1, Fig. 2 and Fig. 3 and has a sleeve 7 threaded on to its lower end. This sleeve 7 in combination with the fingers 8 and the retainer block 9 serve as a setting tool to support the well bottom assembly indicated generally at 10. The well bottom assembly is preferably made up of a set shoe 15 which has threaded to it a sleeve 16 which forms part of the shoe. A back pressure valve 17 may be disposed inside of the shoe and a wash valve 19 may be also carried in the upper end of this shoe. A coupling 20 serves to connect the set shoe with the strainer 22 and these parts are assembled in the order named as this apparatus is made up at the surface. Any desired length of strainer 22 may be added depending upon the depth of the productive formation and above this strainer will be blank pipe or liner 24 of a sufficient length to position the packer 25 within the lower end 26 of the casing 2. A packer setting sleeve 28

projects above the packer and may be of any desired length to terminate in the head 29.

While the well bottom is being assembled at the surface, suitable lengths of wash pipe 5 may 5 be assembled at the same time so that the entire well bottom may be supported by the string of tubing which is connected to the threads 3. This assembly is then lowered into the well by adding lengths of tubing. The lowering operation continues until the set shoe 15 rests upon 10 the bottom of the well bore.

The usual practice, however, is to assemble and lower the well bottom and to then lower the wash pipe 5 and tubing into the well bottom and 15 connect the pipe 5 to the upper end of the sleeve 1. The entire assembly is then lowered into the well. An advantage of the present arrangement is due to the fact that if a bridge in the well bore is encountered the entire assembly may be 20 rotated without in any way affecting the arrangement of the parts used in the setting operation.

It is the usual practice to then circulate clear water downwardly through the wash pipe 5 25 through the openings 30 in the wash valve 19 and the pressure of this water will open the back pressure valve 17 so that there will be a circulation of this water upwardly through the well bore to displace the drilling mud. This flow of wash 30 water will move upwardly around the screen and into the annular space 31 between the packer and the casing. Naturally some of this water will flow inwardly through the strainer 22 and upwardly through the assembly into the casing 2. 35 This washing operation can be continued until the pressure on the formation has been reduced the desired amount due to the reduction in the specific gravity of the column of liquid in the well bore, or it may be continued until clear water returns from the well. In either event 40 when the well has been washed the desired amount, it is then intended that the wash valve 19 shall be closed and the setting string released from its connection at the lower end of the strainer. To accomplish both the release of the 45 setting tool and the closing of the wash valve a plug 40 will be deposited in the upper end of the setting string and pumped downwardly by the flow of washing liquid. This plug is formed with 50 a sealing flange 41 so that it will be carried along inside of the wash pipe 5 and is also provided with a shoulder 42 which is arranged to abut upon a shoulder 43.

The retainer block 9 has been positioned 55 between the lower end of the sleeve 1 and the inside of the resilient fingers 8, after these fingers have been moved into the threaded contact 45 inside of the coupling 20, a locking or shear pin 46 having been inserted to normally hold the block in 60 the position shown in Fig. 3. It will be understood that the load of the well bottom is transmitted by the threaded connection 45 through the fingers 8 to the wash pipe 5.

It will be noted that the sleeve 1 fits in the 65 depression 47 so as to confine the flow of liquid downwardly through the wash pipe to the inside of the block 9 and in this manner hydraulic pressure can be applied to the plug 40 to provide a sufficient force to shear the pin or pins 46. When 70 the shearing operation occurs the block 9 and the plug 40 will be caused to move downwardly due to this hydraulic pressure and will assume the position shown in Fig. 4 so that the block 9 closes the openings 30 in the wash valve 19. As this 75 block 9 moves downwardly from its position

within the lower end of the spring fingers 8, these fingers will snap inwardly to the position shown in Fig. 4 until they abut against the sleeve 1. This radially inward movement releases the threaded connection 45 so that the setting string 5 is now released from the well bottom. If it is desired to wash the inside of the screen, the washing fluid can now be pumped downwardly through the setting string and it will move upwardly through the chamber 49 so as to wash in the inside of the screen.

Fig. 6 shows the back pressure valve 64 as having an upstanding flange 91 to telescopically receive the skirt 90 of the wash valve so as to insure a seal. If some obstruction should be 15 about the flange 91, it could be sheared by the skirt 90.

Particular attention is directed to the fact that this releasing operation has been accomplished without any rotation of the parts and that it has only been necessary to lower the well bottom into position, perform the washing operation, introduce the plug 40 and pump it into position to effect the release.

It is now desirable to set the packer 25 which is best seen in Figs. 1 and 2 and to accomplish this the setting string is raised a sufficient amount to carry the setting dogs 50 to an elevation above the head 29. These setting dogs 50 are in the nature of flaring segments whose upper ends are pivoted beneath the flange 51 on the coupling 52 and whose lower ends are normally urged outwardly by the springs 53.

As the setting string is raised upwardly, these dogs 50 will snap outwardly above the head 29 and the setting string can then be lowered so that the dogs will abut against the top 54 of the head 29. The weight of the string of tubing can in this manner be applied to the setting sleeve 28 and it can be caused to move downwardly to collapse the packer 25. Packers of this general type are well known in that they are provided with wrappings of canvas 56 which will expand as the length of the packer is reduced and in this manner a seal will be formed with the inside surface 57 of the casing 2. The setting string or tubing can now be raised to any desired elevation and if the well will flow voluntarily the upper end of the tubing can be opened to permit such flow, or a swab may be run in through the tubing to initiate the flow. On the other hand, if the well is to be pumped, the pump can be lowered into the tubing.

Figs. 5 to 9 inclusive show a slightly different form of the invention where a majority of the parts are the same. In this form, however, the wash valve is indicated at 60 and is of a peculiar configuration to provide stream lined passages 61 which are directed downwardly and the lower end of the wash valve has a conical recess 62 to receive the stem 63 of the back pressure valve 64.

In this form of the invention the block 9 and the wash valve 19 of Fig. 1 have been combined together as the valve extends upwardly and outwardly to include a skirt 66. The locking or shear pin 67 holds this wash valve in open position.

The lower end of the setting string 3 is seen in Fig. 5 and is provided with a coupling or sleeve 69 which has its lower end beveled at 70 to fit upon the shoulder 71 on the inside of the upper end of the wash valve 60. The connection between the setting string 3 and the well bottom assembly 10 is accomplished by a locking ring 73 75

which, as seen in Fig. 8, is made up of a plurality of blocks or segments 74.

These segments are mounted upon a ring or wire 75 which has been compressed when the 5 ring was fitted into the position shown in Fig. 5 so that the beveled face 16 on the blocks will rest against the enlarged portion 17 formed on the outer periphery of the coupling 69. The outer surfaces 18 of these blocks are arranged to fit 10 within the upper end of the wash valve 60 and an inwardly projecting flange 19 on the sleeve 16 of the set shoe 15 is arranged to abut against the top side of this locking ring. A packing ring 80 may be positioned inside of the flange 19 and 15 abut the coupling 69 so as to form a seal with the parts. An enlarged portion 81 on the coupling 69 abuts against the upper side of the flange 19.

With the parts assembled as seen in Fig. 5, it 20 is apparent that there can be no relative movement of the parts and the setting string 3 will be capable of carrying the load of the well bottom assembly 10 due to the positioning of this locking ring 13.

25 The parts will be assembled as described in connection with Fig. 1 and lowered into the well bore. The plug 40 will then be inserted in the setting string and pumped down the same as previously described. When this plug arrives in 30 the wash valve 60 it will cut off the ports 61 as seen in Fig. 5 and the hydraulic pressure can then be applied through the setting string to shear the pin or pins 67. The pressure then serves to move the entire wash valve 60 down- 35 wardly to the position shown in Fig. 6 and this movement brings the skirt 66 downwardly away from the surface 18 of the locking ring 13. The spring wire 15 will then throw the segments 14 outwardly to separate the shoulders 16 and 17. 40 This outward movement of the locking ring releases the coupling 69 and the setting string from its connection with the well bottom assembly. If desired, a snap lock 83 may be provided in the plug to snap into the recess 84 in the wash valve 45 to insure that the plug will not be displaced due to any pressure from below should the back pressure valve 64 leak.

Fig. 7 shows an interfitting arrangement of the coupling 69 by providing the lugs 86 thereon to 50 fit into the depressions 87 in the flange 19. This connection is provided so that if it is necessary to rotate the set shoe 15 in lowering the assembly into the well that such rotation may be effected. In some instances a caving of the well 55 bore has occurred and these cavings must be removed from the well bore by rotating the well bottom and circulating liquid through it.

The setting operation to collapse the packer will be the same with the construction shown in 60 Figs. 5 to 9 as it was in the form shown in Figs. 1 to 4, inclusive.

In some instances a body of clear water is deposited in the well bottom assembly as it is made up and lowered into the well and then 65 sufficient clear water is introduced into the wash pipe to fill the estimated cavity about the screen. The plug can then be inserted and thereafter mud or other liquid used to force the plug down to its seat. When the plug seats and the pressure 70 builds up then the operator knows he has clear water both inside and outside of his screen or strainer. The signal thus obtained is of advantage. The method is practiced where it is contemplated that higher pressures are present and 75 where it might be dangerous to remove the col-

umn of heavier fluid from the well. After the well head fittings have been attached then the well may be opened up to flow and will clean itself.

Broadly, the invention contemplates the combination of a well bottom assembly and a hydraulically releasable setting tool which is connected at the base of the assembly so that the wash valve may be closed and the setting tool released by a single operation and the well completed for production by one trip into the well bore with a combination tubing and setting string of pipe.

What is claimed is:

1. A well bottom assembly comprising a setting string of pipe, a setting tool thereon, a wash pipe below said tool, a set of spring fingers on the lower end of said wash pipe, a sleeve within said fingers and normally holding them in expanded position, a set shoe, a threaded connection between said fingers and shoe, a strainer on said shoe, a wash valve in said shoe, a pin connection normally holding said sleeve within said fingers, and a plug to be pumped down said string and into said sleeve to shear said pin and move 20 said sleeve by hydraulic pressure, the movement of said sleeve releasing the threaded connection of said fingers and shoe so that said string may be raised to operate said setting tool.

2. A well bottom assembly comprising a setting string of pipe, a setting tool thereon, a wash pipe below said tool, a set of spring fingers on the lower end of said wash pipe, a sleeve within said fingers and normally holding them in expanded position, a set shoe, a threaded connection between said fingers and shoe, a strainer on said shoe, a wash valve in said shoe, a pin connection normally holding said sleeve within said fingers, and a plug to be pumped down said string and into said sleeve to shear said pin and move 25 said sleeve by hydraulic pressure, the movement of said sleeve releasing the threaded connection of said fingers and shoe so that said string may be raised to operate said setting tool.

3. In a well bottom assembly a set shoe, a wash valve therein comprising a cylindrical body, lateral ports therein, and a sleeve to telescope into said body to cover said ports to close said valve.

4. In a well bottom assembly a set shoe, a 50 wash valve therein comprising a cylindrical body, lateral ports therein, and a plug member to close said ports so that hydraulic pressure applied to said plug effects movement of said valve.

5. In a well bottom assembly a set shoe, a 55 wash valve therein comprising a cylindrical sleeve body, lateral ports therein, a plug member to close said sleeve body so that hydraulic pressure applied to said plug effects movement of said body, and a setting string to be released from 60 said shoe upon movement of said body.

6. The combination of a well bottom including a set shoe, a sleeve therein, a shoulder on said sleeve, a plug to be pumped into position to abut said shoulder and move said sleeve, and a 65 setting tool connection to be released by said sleeve.

7. A well bottom, a wash pipe, a threaded connection between the bottom and said pipe, and 70 plug means operable by hydraulic pressure to release said connection.

8. A well bottom, wash pipe, a threaded connection between the bottom and said pipe, plug means operable by hydraulic pressure to release 75

- said connection, and a wash valve in said bottom to be closed by said means.
9. A well bottom including a set shoe, strainer, packer and liner, a wash valve in said bottom, 5 a setting string including a setting tool to set said packer, a wash line to wash through said valve, a connection between said line and said bottom at said shoe, and hydraulically operable means to plug said wash line and release said 10 connection.
10. A well bottom including a set shoe, strainer, packer and liner, a wash valve in said bottom, a setting string including a setting tool to set said packer, a wash line to wash through said 15 valve, a connection between said line and said bottom, and hydraulically operable means including a plug movable to release said connection, so that said tool may be raised to set said packer.
11. A well bottom including a set shoe, strainer, packer and liner, a wash valve in said bottom, 20 a setting string including a setting tool to set said

packer, a wash line to wash through said valve, a connection between said line and said bottom, and an hydraulically operable member movable to release said connection, said means being movable to close said wash valve.

12. A well bottom including a set shoe, strainer, packer and liner, a wash valve in said bottom, 5 a setting string including a setting tool to set said packer, a wash line to wash through said valve, a connection between said line and said bottom, and hydraulically operable means to release said connection, said connection including 10 radially movable dogs.

13. A well bottom including a set shoe, strainer, packer and liner, a wash valve in said bottom, 15 a setting string including a setting tool to set said packer, a wash line to wash through said valve, a connection between said line and said bottom, and hydraulically operable means to release said connection, said connection including 20 radially movable spring fingers.

RURIC N. BEAN.
